UNITED STATES PATENT OFFICE

JAMES G. SCOTT, OF WASHINGTON, DISTRICT OF COLUMBIA

DESIGN FOR A REFRIGERATOR

Application filed March 25, 1930. Serial No. 35,019. Term of patent 14 years.

To all whom it may concern:

Be it known that I, JAMES G. SCOTT, a citizen of the United States of America, and residing in Washington, in the District of Columbia, have invented a new, original, and ornamental Design for Refrigerators, of which the following is a specification, reference being had to the accompanying drawing, forming a part thereof.

The figure is a perspective view of the refrigerator, showing my new design.

I claim:

The ornamental design for a refrigerator, as shown.
